INVENTOR,
William Francis Tritchler,
BY *Frank S. Adelmann*,
ATTORNEYS.

UNITED STATES PATENT OFFICE.

WILLIAM FRANCIS TRITCHLER, OF FARGO, NORTH DAKOTA.

DISPLAY BRACKET.

Application filed December 12, 1925. Serial No. 74,978.

This invention relates to display brackets for merchandise, and particularly to a bracket for displaying footwear such as shoes or the like.

5 It is an object of this invention to produce a bracket which may be detachably applied to a shoe box, whereby a shoe may be supported exteriorly of the box for the purposes of display.

10 It is a further object of this invention to produce a bracket or support which may be expeditiously applied to or removed from shoe boxes and in which the bracket is securely anchored to accomplish the purposes 15 intended.

It is a still further object of this invention to produce a shoe display bracket which can be formed of a single piece of material and in which the material is shaped to provide 20 an anchor for engaging the heel of a shoe and retaining it in place.

With the foregoing and other objects in view, the invention consists in the details of construction, and in the arrangement and 25 combination of parts to be hereinafter more fully set forth and claimed.

In describing the invention in detail, reference will be had to the accompanying drawings forming part of this application where- 30 in like characters denote corresponding parts in the several views, and in which—

Figure 1 illustrates a view in perspective of a fragment of the box showing a device embodying the invention applied thereto; 35 and

Figure 2 illustrates a sectional view of the box and a bracket thereon.

In these drawings, 5 denotes a box and 6 the cover therefor, which may be of any conventional type.

The bracket comprises a slightly curved

inclined shoe support 7 terminating at its upper end in a loop or hook 8 which embraces the upper edge of the box whereon the bracket is anchored. An ear 9 is struck 45 upwardly from the inclined curved portion 7 and preferably the ear is flared in width toward its upper end in order that it will have a relatively wide bearing on the heel 10 of the shoe 11.

50 The bracket has an approximately horizontal integral prop or stay 12 which terminates in an angularly disposed and upwardly extending foot or bearing plate 13 which engages the outer surface of the box near its 55 bottom, against which it is held by the weight of the bracket and the object which it supports.

As has been stated, a device of the character may be manufactured by the ordinary 60 metal stamping processes, and it can be formed from sheet metal or fibrous stock such as cardboard or the like, and made at a comparatively small cost.

I claim:

65 In a display bracket, a member having an inclined shoe supporting surface terminating at its upper end in a hook for embracing the edge of a box and having a portion adapted to lie parallel with the side of the 70 box and a flange of the lid between the said side of the box and the flange of the lid, the said member having an approximately horizontally disposed integral bracing member merging with the inclined portion at the 75 lower end of said inclined portion, the said bracing member having an angularly disposed portion for bearing against the outer surface of the box, and a shoe heel engaging part on the inclined portion in spaced 80 relation to the hook.

WILLIAM FRANCIS TRITCHLER.
